(57) **CLAIM**

We claim the ornamental design for a toolbox, as shown and described.

DESCRIPTION

FIG. 1 is an exploded top perspective view of a toolbox, showing my new design;

FIG. 2 is an exploded top plan view with the interior tray shown adjacent to the tool box for convenience of disclosure;

FIG. 3 is a top perspective view thereof;

FIG. 4 is a bottom perspective view thereof;

FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof; and,

FIG. 10 is a bottom plan view thereof.

The broken lines illustrate portions of the toolbox and form no part of the claimed design.
